CASPER MEHLUM, OF CAMBRIDGE, MASSACHUSETTS.

MACHINE FOR MAKING HARD SHEET FIBER.

1,124,937.

Specification of Letters Patent.

Patented Jan. 12, 1915.

Application filed October 23, 1913. Serial No. 796,932.

To all whom it may concern:

Be it known that I, CASPER MEHLUM, a subject of the King of Norway, residing at Cambridge, county of Middlesex, State of Massachusetts, have invented a certain new and useful Improvement in Machines for Making Hard Sheet Fiber, of which the following is a specification, reference being had therein to the accompanying drawings.

10 In the manufacture of hard sheet fiber as heretofore practised it has been customary to first form a pulp and then to form this pulp into a web or sheet run on a roll and from this roll to rewind it on a mandrel for a sufficient number of layers or windings to make a tube of the thickness required for the hard fiber. After the tube has been built up to the requisite thickness by successive layers of the thin web of 15 fiber, the tube or cylinder thus formed is slashed lengthwise of the mandrel and the slit tube being removed from the mandrel is flattened out and pressed to form a flat sheet. It is found by experience that by 20 building the fiber up in the form of a tube and then slashing it and flattening it out it can be formed of only a very limited thickness. There has been, however, a constantly 25 growing demand for hard sheet fiber for various uses of a considerably greater thickness than it has been possible to make by 30 the method above described.

The object of the present invention is to produce a machine whereby flat sheets or 35 blocks of fiber may be formed of very much greater thickness than can be produced by the previous methods described.

Briefly, it consists of an apparatus by 40 which the sheet is built up in original flat form instead of first building it in cylindrical form and then slitting and flattening it.

The invention will be understood from the following description taken in connection with the accompanying drawings and 45 the novel features thereof will be pointed out and clearly defined in the claims at the close of the specification.

In the drawings,—Figure 1 is a side elevation of a machine embodying the invention. Fig. 2 is a front elevation of the machine shown in Fig. 1. Fig. 3 is a plan of the table at the end of its forward feed stroke, showing it in engagement with the cam block which raises the feed roll. Fig. 55 4 is a diagram showing the feed roll, table,

and web of fiber in the position they occupy at the beginning of a stroke. Fig. 5 is a side view of a portion of the machine showing the feed roll elevated by the cam block to permit the retrograde movement of the 60 table after the forward stroke. Fig. 6 is an enlarged sectional detail view showing the operation of the knives.

Referring now to the drawings, 1 represents the frame or bed of the machine. 65

2 represents the web or sheet which is run from a roll, not shown, thence through an acid bath in the tank 3, as for instance by first passing over a roll 4, thence down into the tank beneath the rolls 5, 6; thence 70 up over the roll 7; whence it passes to a feed roll 8. The roll 8 acts both as a feed roll and a presser roll which carries the web of fiber around onto a flat table 9 which has a reciprocating movement for a 75 stroke equal in length to the circumference of the feed roll 8. The ends of the roll are provided with heads having tubular journals 31 and the roll is heated by steam introduced through the tubular journals by 80 pipes 68. These pipes 68 are flexible to allow for the rise and fall of the roll. Means are provided for cutting the web lengthwise of the feed roll 8 once at each rotation of the said roll so that sheets equal 85 in length to the circumference of the roll 8 will be formed and will be superposed one upon another upon the table 9 and pressed together by the roll 8 as the table travels beneath the roll, said roll 8 being 90 journaled in vertically movable bearings so that the roll 8 may be lifted after the table has moved in one direction under the pressure roll to allow the table to return without interference with the roll, and also to 95 allow for the building up of the sheet. This mechanism will be now more particularly described.

The table 9 is preferably made of metal and also hollow to permit the introduction 100 of steam through the pipe 10 for the purpose of warming the table. This table is fixedly mounted upon rails 11, 11, extending lengthwise of the table, said rails each resting upon a series of rolls 12 which are 105 pivoted in standards 13 mounted upon the base of the machine. Said rolls 12 are each formed with peripheral flanges 14, 14, thereby forming a grooved way to receive the foot of the rail 11, and thereby forming 110

guides for the travel of the rails and supported table 9. Means are provided for giving to the rails 11 and the table 9 mounted fixedly thereon reciprocable movement equal in length at each forward and each back stroke a distance equal to the circumference of the roll 8. The means as shown are as follows: A lever 15 is pivoted at one end to a lug 16 secured to the under side of the table at 5 one end thereof, the other end of said lever 15 being pivoted at 17 to one end of a lever 18, the other end of said lever 18 being pivoted at 19 to a hanger 20 which is supported from the overhead frame work 21. Said 10 lever 18 is pivotally connected at 22 with one end of the crank lever 23, the other end of said crank lever 23 having a pivot connection at 24 with a gear wheel 25 journaled at 26 in bearings in a hanger 27 supported from the overhead frame 21. Said gear 25 15 meshes with a pinion 28 mounted on a shaft 29, said shaft also carrying a driving pulley 30. The train of gearing is of such proportions that the table 9 will be reciprocated at each stroke in either direction a distance equal to the circumference of the roll 8 as already described. It is obvious that any suitable train of gearing or other mechanism may be adopted for giving reciprocation to 20 the table 9 which will be an equivalent for the reciprocating mechanism already described.

The feed roll or cylinder 8 is provided with journals 31 journaled in the bearing blocks 32 which are respectively hung by chains or other flexible connections 33 from wheels 34 mounted on opposite ends of a shaft 35. Said shaft 35 is journaled in the levers 52 fulcrumed at one end on shaft 53, the 25 other end of each lever resting on the upper end of a rod 50, as will be hereinafter explained. Said chains or flexible connections 33 are made fast at one end to said wheels 34 so that the said chains will wind around the wheels to raise or lower the said blocks 32. The said blocks 32 move in vertical guideways formed by a groove or slot in the vertical guides 36, 36. A worm screw 37 mounted on a shaft 38 engages with a worm 30 wheel 69 on the shaft 35 whereby the said shaft 35 and therefore the wheels 34 may be rotated if desired, said shaft 38 being provided with a hand wheel 39 whereby the shaft may be rotated at the will of the operator when desired, as for instance to lower the feed roll 8 down to the table after a built up sheet or block has been removed so as to start a new sheet. In the usual 35 operation of the machine, however, during the building-up of the sheet the necessary raising and lowering of the feed roll 8 and its bearings will be accomplished automatically. Mounted on the shaft 38 is a sheave 40 to which is secured one end of a rope 41, 40 said rope passing up over a pulley 42 which

is journaled in bearings in the hanger 43 hung from the overhead support 21, and the end of said rope 4 is secured to a weight 44 which has the effect of taking up the slack which is occasioned by the slight increase 70 in thickness of the sheet being built up after each ply is laid on. That is, at each time after a ply has been laid on the sheet being built up on the table, as the roll 8 drops down it will not drop so low as before by a distance 75 equal to the thickness of the ply. This will tend to leave a slack in the chain 33 by just so much as occasioned by the thickness of the ply. In order to take up this slack the chain wheels 34 should be slightly turned, 80 and this is done by the weight 44 which pulls the rope 41 and thence turns the shaft 38 and worm 37 to turn the worm wheel 69 and wheels 34.

Rising from the base of the machine on 85 each side of the table 9 is a standard 45, and from the inner face of each of said standards 45 there project the slotted lugs 46, 46 which serve as supports and guideways for the slidable cam blocks 47. Said cam blocks 90 are each formed with a hump or elevated flat portion 48 reached from one end by an inclined face 49. A vertically movable rod 50 is pivotally connected at its lower end with a roll 51 which rests upon said cam block 47 and its upper end supports one end of the lever bearing 52 in which the shaft 35 and the chain wheel 34 are journaled, as previously described, so that as said vertical rod 50 moves upward it will lift the free end 100 of the lever bearing 52 and turn it upward, thereby lifting the wheel 34 and the bearing blocks 32 and feed roll 8. The said rod 50 passes through suitable guides, as for instance 54, 54. Projecting from the inner 105 face of each of the cam blocks 47 is a lug 55.

Projecting from the outer edge of the table 9 on both sides near the forward end are lugs 56 and projecting from the same edges of the table 9 near the rear end are 110 lugs 57. Near the end of the forward movement of the table the lugs 57 will engage the lugs 55 and slide the cam block 47 forward in its guides, causing the inclined face 49 of the cam block to ride under the roll 51 and thereby lift the roll 51 up onto the flat elevated portion 48 of the cam block, and thereby turn up the lever bearing 52 and the bearing blocks 32, and thus raise the roll 8 already described. During the 115 return movement of the table 9 the said rod 50 will remain in its elevated position with the roll 51 resting on the elevated portion 48 of the cam until the table has reached nearly the end of its backward stroke when the lug 56 will engage the lug 55 and push the cam block 47 backward, allowing the roll 51 to follow down the inclined face 49 as the weight of the bearing blocks 32 will be sufficient to pull down the lever bearing 120 125 130

52 by gravity and bring the feed roll 8 down in contact with the sheet, and the weight 44 will take up the slack of the chain 33 as already described.

- 5 Extending lengthwise of the feed roll 8 slightly clearing the periphery of the roll is a stationary blade 58 mounted at each end in suitable supports 59. Means are provided by which the said blade 58 may be adjusted 70 to a greater or less distance from the roll 8. For instance, as shown, the bearings 59 are each formed with a slot 60 to receive the ends of the blade 58, the blade being clamped therein by a clamp screw 61 which 75 15 passes through the wall of the bearing 59 and a stop screw 62 passes through the outer end of the bearing 59 and impinges on the back of the blade 58, said stop being adjustable to limit the outward adjustment of the 20 blade 58 and prevent it from being pushed back by the pressure of the other blade during the cutting operation. Preferably this blade 58 is made of a broad obtuse angled V-shape so that the sheet will be sheared off 25 gradually instead of being cut instantly.

The feed roll 8 is formed with a peripheral slot 63 lengthwise of the roll within which is a blade 64. At each end of the said blade 64 there is secured one end of a 30 spring 65, the other end of said spring being secured to the head of the feed roll 8, the tension of said springs 65 being such as to normally hold the blade 64 down within the slot in the feed roll without projecting 35 beyond the periphery of the feed roll. Cam plates 66 are mounted on the frame at each end of the feed roll in such position that a cam face 67 will during the rotation of the feed roll be engaged by the projecting end 40 of the blade 64 just before it reaches the stationary blade 58 and push the blade 64 outward in the slot so that its cutting edge projects beyond the periphery of the feed roll and thereby engages the film of fiber on the 45 periphery of the feed roll, the cutting edge of the fixed blade 58 thereby causing the sheet of fiber to be cut crosswise by the shearing blades already described. By the use of the angular shaped blade 58 as de- 50 scribed the cutting will begin at the two outside edges and cut simultaneously toward the middle, forming a V-shaped cut. As soon as the blade 64 in the rotation of the feed roll rides past the cam 66, the pull 55 of the spring 65 will pull the blade 64 into the slot within the periphery of the feed roll. The stationary knife is located slightly above the table so that the cutting takes place shortly before the line of the cut of 60 the sheet reaches the table and just before the end of the forward movement of the table. The rear end of the portion cut off will be pressed down onto the table or onto the partially built up sheet already formed, 65 as the table completes its forward stroke.

The web back of the cut will naturally adhere to the periphery of the feed roll even after it is cut until it reaches the table. As soon as the end of the web just back of the portion cut off reaches the table and begins 70 to pass between the lower surface of the feed roll and the table, the feed roll will have been dropped into its lowermost position so that it will by its own weight press the web against the table or against the up- 75 80 85 90 95 100 105 110 115 120 125 130 permost ply already on the table. The mechanism for actuating the table 9 is adjusted, as already described so that as soon as the table has completed its forward movement, and the sheet already cut off has been laid down, the table will return and be in position to receive the new advance end of the web and the roll 8 will come down into pressing engagement with it. The table will then move forward a full stroke carrying forward the web which as it is pressed down by the feed roll will move with the table and draw the web from the roll 7 as already described until the table reaches the end of its forward stroke. Just before it reaches 90 the forward end of its stroke the web will be cut by the blades as already described. At the end of the forward stroke the feed roll is lifted by the cam 47, actuated by the lug 57 on the table engaging with the lug 55 95 on the cam block 47. The table 9 then will move on its backward stroke but the feed roll 8 will not rotate because there is no frictional contact between the table and the periphery of the feed roll. When the table is moved its backward stroke and the cam block 47 has been moved so as to bring the feed roll down into contact with the new end of the web the table will move forward again and the web of fiber will be fed forward, superimposing another layer upon the first layer until the end is cut off when the operation already described will be repeated.

What I claim is:

1. In a machine for making sheet fiber, by building it up with successive layers of fiber, a reciprocable element having a flat surface on which the sheet is built up, a rotary presser roll above said flat surface yieldingly mounted in bearings which allow movement toward and from said flat surface, said presser roll acting also as a feed roll for feeding a web of fiber between said flat surface element and said presser roll, and means for sliding said flat surface while the presser roll presses the web of fiber on said flat surface.

2. In a machine for making sheet fiber by building it up with successive layers of fiber, a flat reciprocable table on which the sheet is built up, a rotary feed roll which carries the web of fiber to the table, means for reciprocating the table beneath said feed roll, said feed roll serving also as a presser roll which presses each successive layer of fiber 130

onto the plies on which it is superimposed, and means for severing each layer from the web.

3. In a machine for making sheet fiber by building it up with successive sheets of fiber, a flat reciprocable table on which the sheet is built up, a rotary feed roll which carries a web of fiber to the table, means for reciprocating the table beneath said feed roll, 10 said feed roll serving also as a presser roll which presses each successive layer of fiber onto the sheets on which it is superimposed, and means for severing the web at each rotation of the said roll thereby forming successive sheets equal in length to the circumference of the feed roll.

4. In a machine for making sheet fiber by building it up with successive plies of fiber, a rotary feed roll which carries the web of fiber to the table, means for reciprocating the table beneath said feed roll, said feed roll serving also as a presser roll which presses each successive layer of fiber onto the sheets on which it is superimposed, 20 means for severing the web at each rotation of the said roll thereby forming successive sheets equal in length to the circumference of the feed roll, and means for raising the said feed roll out of contact with the top- 25 most sheet on the table at the end of each forward stroke of the table and maintaining it in an elevated position during the backward movement of the table.

5. In a machine for making sheet fiber, a flat reciprocable table on which the sheet is built up with successive plies of fiber, a rotary presser roll journaled above said table and adapted to engage with the table, said presser roll acting also as a feed roll for 35 feeding a web of fiber onto the table beneath the presser roll, means for reciprocating said table whereby during the movement in one direction the plies of fiber between the table and the presser roll will be pressed together, 40 and means for severing the web for each successive layer.

6. In a machine for making sheet fiber, a flat reciprocable table on which the sheet is built up with successive sheets of fiber, a rotary presser roll journaled above said table and adapted to engage with the table, said presser roll acting also as a feed roll for feeding a web of fiber onto the table beneath the presser roll, means for reciprocating said 50 table whereby during its movement in one direction the plies of fiber between the table and the presser roll will be pressed together, means for severing the web for each successive ply, and means for raising said 55 presser roll out of engagement with the sheet on the table at the end of the forward movement and retaining it in its elevated position during the backward movement of the table.

65 7. In a machine for making sheet fiber, a

flat reciprocable table on which the sheet is built up with successive layers of fiber, a rotary presser roll journaled above said table and adapted to engage with the table, said presser roll acting also as a feed roll for 70 feeding a web of fiber onto the table beneath the presser roll, means for reciprocating said table whereby during the movement in one direction the layers of fiber between the table and the presser roll will be pressed together, means for raising said presser roll out of engagement with the sheet on the table at the end of the forward movement and retaining it in its elevated position during the backward movement, and means for 75 severing the web of fiber at each rotation of the presser roll to form sheets.

8. In a machine for making sheet fiber, a flat reciprocable table on which the sheet is built up with successive plies of fiber, a rotary presser roll journaled above said table and adapted to engage with the table, said presser roll acting also as a feed roll for feeding a web of fiber onto the table beneath the presser roll, means for reciprocating said 80 table whereby during the movement in one direction the plies of fiber between the table and the presser roll will be pressed together, means for raising said presser roll out of engagement with the sheet on the table at the 85 end of the forward movement and retaining it in its elevated position during the backward movement, and means controlled by the movement of the presser roll to cut successive sheets from the web of uniform 90 length.

9. In a machine for making sheet fiber, a flat reciprocable table on which the sheet is built up with successive plies of fiber, a rotary feed roll over the table which feeds the 105 web of fiber onto the table and under the feed roll, said feed roll being journaled in vertically movable bearings above the table, means for reciprocating the table whereby when the table moves in one direction the 110 web will be clamped by the feed roll to the table and will transmit rotary movement to the feed roll, means for severing the web of fiber at each rotation of the feed roll, means for lifting the feed roll from engagement 115 with the sheet on the table before the return stroke of the table and maintaining it in its elevated position during said return stroke, and means whereby the feed roll is again lowered into pressing engagement with the 120 sheet on the table for another feed movement.

10. In a machine for making sheet fiber, a flat reciprocable table on which the board is built up with successive plies of fiber, a rotary feed roll over the table which feeds the 125 web of fiber onto the table and under the feed roll, said feed roll being journaled in vertically movable bearings above the table, means for reciprocating the table whereby 130

when the table moves in one direction the web will be clamped by the feed roll to the table and will transmit rotary movement to the feed roll, means for severing the web of fiber at each rotation of the feed roll, means for lifting the feed roll from engagement with the sheet on the table before the return stroke of the table and maintaining it in its elevated position during said return stroke, and means whereby the feed roll is again lowered into pressing engagement with the sheet on the table for another feed movement, the actuating mechanism for the table being so regulated that the length of stroke 10 of the table in each direction will be equal to the circumference of said feed roll.

11. In a machine for making sheet fiber, a flat reciprocable table on which the sheet is built up by a succession of plies of fiber, a rotary feed roll over the table which feeds the web of fiber onto the table and under the feed roll, said feed roll being journaled in vertically movable bearings above the table, means for reciprocating the table 20 whereby when the table moves in one direction the feed roll will press the web on the table and thereby transmit rotary movement to the feed roll, a vertically movable support for the bearings of the feed roll, means for severing the web for each successive ply, a cam, means whereby the table actuates the cam near the end of the forward feed movement, intermediate connections whereby said movement of the cam elevates the said feed 30 roll bearings, and means whereby the table near the end of its return movement moves the cam to release the said feed roll bearings from the elevated position and allows the feed roll to again engage with the sheet on 35 the table.

12. In a machine for making sheet fiber, a flat reciprocable table on which the sheet is built up with successive layers of fiber, a rotary feed roll over the table which feeds the web of fiber onto the table and under the feed roll, said feed roll being journaled in vertically movable bearings above the table, means for reciprocating the table whereby when the table moves in one direction the 45 web will be gripped by the feed roll to the table and will transmit rotary movement to the feed roll, a stationary blade mounted alongside of the periphery of the feed roll, the feed roll being formed with a longitudinal slot in the periphery thereof, a movable blade set into said slot, springs which normally hold said blade sunk in said slot below the surface of the periphery, and means which move said blade outwardly in said slot at a predetermined point in the rotation of the feed roll when in its rotation 50 it comes opposite the said stationary blade and retains said movable blade in position to co-operate with said stationary blade to sever the web, said springs causing the retraction of said movable blade into the slot in the roll after the movable blade has ridden past the stationary blade, means for lifting the feed roll from engagement with the sheet on the table before the return stroke of the table and maintaining it in its elevated position during said return stroke, and means whereby the feed roll is again lowered into pressing engagement with the sheet on the table for another feed movement.

13. In a machine for making sheet fiber, a flat reciprocable table on which the sheet is built up with successive layers of fiber, a rotary feed roll over the table which feeds the web of fiber onto the table and under the feed roll, said feed roll being journaled in vertically movable bearings above the table, means for reciprocating the table whereby when the table moves in one direction the web will be gripped by the feed roll to the table and will transmit rotary movement to the feed roll, a stationary blade 70 mounted alongside of the periphery of the feed roll, the feed roll being formed with a longitudinal slot in the periphery thereof, a movable blade set into said slot, springs which normally hold said blade sunk in said slot below the surface of the periphery, and means which move said blade outwardly in said slot at a predetermined point in the rotation of the feed roll when in its rotation 75 it comes opposite the said stationary blade and retains said movable blade in position to co-operate with said stationary blade to sever the web, said springs causing the retraction of said movable blade into the slot in the roll after the movable blade has ridden past the stationary blade.

14. In a machine for making sheet fiber, a flat reciprocable table on which the sheet is built up with successive layers of fiber, a roll journaled above the table which feeds the web of fiber onto the table, means for reciprocating the table whereby when the table moves in one direction the web will be gripped by the roll to the table, and means for severing the web of fiber at each rotation of the feed roll.

15. In a machine for making sheet fiber 100 by building it up with successive plies of fiber, a reciprocable table on which the sheet is built up, a rotary feed roll which carries the web to the table and beneath the feed roll, means for reciprocating said table beneath the feed roll, said feed roll normally resting on the top ply and serving as a presser roll during the forward movement of the table and fiber, means for severing the web for each successive ply, vertically movable mountings for the feed roll whereby the feed roll is permitted to be raised and lowered, a vertically movable support having a flexible connection with the mountings for the feed roll, and means actuated 105

110

115

120

125

130

by the movement of the table to raise said flexibly connected support and thereby raise the feed roll.

16. In a machine for making sheet fiber by building it up with successive plies of fiber, a reciprocable table on which the sheet is built up, a rotary feed roll which carries the web to the table and beneath the feed roll, means for reciprocating said table beneath the feed roll, said feed roll normally resting on the top ply and serving as a presser roll during the forward movement of the table and fiber, means for severing the web for each successive ply, vertically movable mountings for the feed roll whereby the feed roll is permitted to be raised and

lowered, a vertically movable support having a flexible connection with the mountings for the feed roll, means actuated by the movement of the table to raise said flexibly connected support and thereby raise the feed roll, and means for taking up the slack in the flexible connection of the said mountings due to the shortening of the downward movement as the sheet is built up. 20 25

In testimony whereof I affix my signature, in presence of two witnesses.

CASPER MEHLUM.
